(12) **United States Design Patent**
Diebel(10) **Patent No.:** **US D750,632 S**
(45) **Date of Patent:** **** Mar. 1, 2016**(54) **COVER FOR ELECTRONIC TABLET**(71) Applicant: **Incase Designs Corp.**, Chino, CA (US)(72) Inventor: **Markus Diebel**, San Francisco, CA (US)(73) Assignee: **Incase Designs Corp.**, Chino, CA (US)(**) Term: **14 Years**(21) Appl. No.: **29/469,241**(22) Filed: **Oct. 8, 2013****Related U.S. Application Data**

(63) Continuation of application No. 29/419,054, filed on Apr. 24, 2012, now Pat. No. Des. 691,143, which is a continuation of application No. 29/388,000, filed on Mar. 22, 2011, now Pat. No. Des. 658,188, and a continuation of application No. 29/387,775, filed on Mar. 17, 2011, now Pat. No. Des. 658,187.
